GAS HOLDER WITH CONSTANT PRESSURE

Heinz Otto Hohl, Vienna, Austria, assignor of
one-half to the firm Paul Haack, Vienna,
Austria, a firm composed of Wilhelm Haack and
Alfred Haack

Application March 23, 1933, Serial No. 662,316
In Austria May 17, 1932

8 Claims. (Cl. 23—259)

Liquid sealed gas holders have heretofore been subject to the disadvantage that the gas pressure does not remain constant during discharge but gradually decreases. Consequently experimental work which calls for a uniform current of gas for a considerable length of time, such, for instance, as combustion analysis, calorific tests of gases and so forth, requires constant attention for regulation of the gas pressure. However for laboratory use, gas storage holders are already known which maintain a constant pressure, but their manipulation is normally somewhat difficult, particularly during charging.

The present invention relates to an improved constant pressure gas-holder of the kind comprising a gas compartment and a liquid compartment which is in communication with the former by a pipe extending into said gas compartment and terminating close to the bottom thereof.

The essential feature of the gas-holder according to the present invention consists in that the liquid compartment is constructed so as to act like a Mariotte's bottle, which consists of a sealed bottle having an outlet in its lower part and an atmospheric tube dipping below the surface of the liquid therein, so that, after liquid has been discharged until air bubbles into the bottle through the atmospheric tube, the liquid discharges under a constant pressure and at a constant speed which depends upon the level of liquid between the bottom of the atmospheric tube and the outflow opening of the bottle; the pressure and speed of outflow naturally decreasing as the atmospheric tube is lowered towards the outflow opening of the bottle. In the case of this invention, the communication pipe extending into the gas compartment is provided with an overflow pipe discharging within said gas compartment. Preferably an automatically operating cut-off device is arranged in an air vent of the cover or stopper of the liquid compartment and also, if desired, in the communication pipe and in the overflow pipe.

The overflow pipe branches off from the side of the communication pipe, or is arranged to surround the same.

Some modes of carrying out the present invention are illustrated on the accompanying sheet of drawing in which Fig. 1 shows the gas-holder in sectional elevation. Figs. 2, 3 and 4 illustrate different constructions of the communication pipe and overflow pipe disposed within the gas compartment.

The gas compartment or gas storage compartment 1 is closed by a removable cover or stopper 2 from which branches off a gas pipe 4, con-

trolled by a stop valve 3. A pipe 5 passes gas-tight through the cover 2 and terminates in the gas compartment 1 near the floor thereof. Some distance from its bottom end, the pipe 5 is provided a flap valve 6, which permits the admission of the sealing liquid from the gas compartment 1 into the pipe 5 but prevents the discharge of said liquid from said pipe 5. In the construction shown in Fig. 1, an overflow pipe 7 branches off from the communication pipe 5 above the valve 6 and terminates near the cover 2. A flap valve 8, arranged in said overflow pipe, permits the passage of the sealing liquid from the pipe 5 into the pipe 7. The liquid compartment 9, containing the sealing liquid, is arranged above the gas compartment 1 and is in communication therewith by the pipe 5. This compartment 9 is closed by a removable stopper or cover 10, through which passes gas-tight an air suction pipe 12, which may be provided with a stop valve 11 and extends close to the floor of the liquid compartment 9 and renders possible the characteristic action of the Mariotte's bottle. A short pipe 13 is connected with the cover 10 and provided with a flap valve 14, permitting the escape of air from said compartment 9 but not the admission of air into the latter. A flexible pipe or thick-walled rubber tube is used in place of the pipe 5, which renders possible the rearrangement of the sealing liquid compartment 9, in case the device is used for the discharge of gas at different pressures. This is a requirement also in the case of a gas compartment with gases at atmospheric pressure, as it will be described hereinafter.

If it is desired to charge the device with sealing liquid, the cover 10 of the compartment 9 is removed, while the stop valve 3 of the compartment 1 is opened and now the sealing liquid flows through the communication pipe 5 thereby shutting the flap valve 6 of the latter and opening the flap valve 8 of the overflow pipe 7. Now the liquid flows over the top of the latter into the gas storage compartment 1. The air, displaced in the latter by the sealing liquid, escapes by way of the pipe 4. Sealing liquid is supplied until it begins to pass out through the pipe 4. Now the stop valve 3 is shut and so much sealing liquid is still filled in until it extends somewhat above the bottom end of the air suction pipe 12, which with its cover 10 is mounted in position. Now the gas compartment is ready for the charging with gas. This may be carried out in different ways, which depends on whether the gas to be supplied is or is not subjected to a higher pressure.

The supply with gas at a higher pressure is carried out in the following manner:—The reducing valve of a steel bottle filled with gas under high pressure is secured to the pipe 4, and now 5 the stop valve 3 and subsequently the said reducing valve are opened. Gas flows into the gas compartment 1 and ultimately produces an over-pressure therein. Thus the flap valve 8 is held shut, while the valve 6 is opened by the sealing 10 liquid rising in the pipe 5. Now the liquid flows into the compartment 9 and compresses the air within the latter to such an extent until the valve 14 is opened and escapes by way of the vent 13. The reducing valve of the steel bottle as well 15 as the stop valve 3 are shut and the steel bottle is removed, if the storage compartment 1 is filled with gas and practically the entire sealing liquid has been forced into the compartment 9.

Now the gas within the compartment 1 is 20 subjected to a pressure, which corresponds to the height of the liquid-column, resulting from the difference of the liquid levels in the compartments 1 and 9 increased by the pressure necessary for lifting the valves 6 and 14. For 25 actual use, this pressure has to be reduced to the experimental pressure, which is accomplished by opening the stop valve 3 and allowing the escape of such quantity of gas until air bubbles arise in the sealing liquid at the bottom opening 30 of the air suction pipe 12. Thereby the following has taken place:—In view of the escape of gas from the gas compartment 1, the gas-pressure in the latter sinks and therefore the sealing liquids flows from the compartment 9 into the 35 compartment 1, whereby partial vacuum is produced in the compartment 9 above the liquid. Therefore the valve 14 is closed automatically and air enters by way of the pipe 12 into the compartment 9. Even in the event of a further 40 discharge of gas, the pressure remains constant because now the characteristic effect of the Mariotte's bottle is produced. This constant pressure is the result of the level-difference H .

A vacuum pump (water jet pump) is secured 45 to the pipe 13 if the gas is subjected to atmospheric pressure for instance if the compartment 1 is to be filled with air. The stop valve 11 of the air suction valve 12 is shut, while the stop valve 3 of the pipe 4 is opened, and now air is 50 sucked out of the compartment 9. The sealing liquid rises in the latter and air passes through the pipe 4 into the compartment 1. The constant pressure is set automatically whenever the stop valve 3 is shut, the pump is removed and 55 the stop valve 11 is opened. Further the gas may be charged in the following manner:—The compartment 9 operating in the manner of Mariotte's bottle is disposed lower than the compartment 1 and a flexible pipe, rubber tube or 60 the like establishes communication between both compartments. A vacuum is produced in the compartment 1 owing to the siphon-action, so that the same is charged with air. The constant experimental pressure is obtained by lifting or 65 adjustment.

The arrangement of the valves in the gas storage compartment 1 can be simplified considerably. As shown in Fig. 2 the overflow pipe 7 and the communication pipe 5 are combined to form a 70 U-shaped pipe and the non-return valve 15, common to both pipes, is disposed close above the floor of the gas storage compartment 1. In the embodiment shown in Fig. 3, the overflow pipe 7a is arranged around the communication pipe 5 and 75 a non-return valve 16 is disposed in the bottom

end of the former. If gas is discharged, the non-return valve 15 or 16 respectively is shut and the sealing liquid flows over the top rim of the overflow pipe 7 or 7a respectively and into the gas storage compartment 1. However when charging with gas the gas-holder, an overpressure is caused within the gas storage compartment 1 and thus the liquid within the overflow pipe is forced upward until the level in the latter has dropped below the outer level. Now the non-return valve gives free the opening, so that the liquid flows outside into the overflow pipe and thus the whole liquid is pressed into the compartment acting in the manner of Mariotte's bottle. Also in these constructions the adjustment to constant pressure is effected by relieving the overpressure, whereby the non-return valve is closed again and the liquid is forced to overflow.

In the construction shown in Fig. 4, the overflow pipe 7b is in the form of a float, which surrounds freely slideable the connection pipe 5. The bottom end of this overflow pipe rests on the floor of the gas storage compartment 1 and is provided with an enlargement acting as float. The concentric location between the two pipes 5 and 7b 100 is secured by means of guides 17 arranged on the inside of the overflow pipe 7b. The bottom end of the latter dips into a thin layer of mercury 18 on the floor of the compartment 1 and thus safeguards a good sealing of said bottom end. If 105 gas is discharged, the overflow 7b rests on the floor of the compartment 1 and therefore the sealing liquid entering by way of the connection pipe 5 flows over the top rim of the overflow pipe 7b and into the compartment 1. When charging with 110 gas, the liquid in the overflow pipe is forced into the compartment acting in the manner of Mariotte's bottle, whereby the level within the overflow pipe sinks below the outside level and thus 115 said pipe is lifted from its seat. Now liquid can flow in.

What I claim is:—

1. In a gas-holder, comprising a gas compartment, a liquid compartment in the form of Mariotte's bottle, a communication pipe branching off from said liquid compartment and extending into said gas compartment and terminating in the latter just above the floor thereof, the provision of an overflow pipe arranged within said gas compartment and in communication with said communication pipe and terminating in said gas compartment above its highest liquid level. 120

2. In a gas-holder, comprising a gas compartment, a liquid compartment in the form of Mariotte's bottle, a communication pipe branching off from said liquid compartment and extending into said gas compartment and terminating in the latter above the floor thereof, the provision of an overflow pipe arranged within said gas compartment and branching off from said communication pipe and terminating in said gas compartment above its highest liquid level. 125

3. In a gas-holder, comprising a gas compartment, a liquid compartment in the form of Mariotte's bottle, a communication pipe branching off from said liquid compartment and extending into said gas compartment and terminating in the latter above the floor thereof, the provision of an overflow pipe arranged within said gas compartment around said communication pipe and terminating in said gas compartment above its highest liquid level. 130

4. Gas-holder with constant pressure, comprising in combination a gas compartment, a liquid compartment in the form of Mariotte's bot- 145

- tle, a communication pipe branching off from said liquid compartment and extending into said gas compartment and terminating in the latter above the floor thereof, a cut-off device in said communication pipe, an overflow pipe arranged within said gas compartment and in communication with said communication pipe and terminating in said gas compartment above its highest liquid level, and a cut-off device in said overflow pipe. 5 munication pipe and resting on the floor of said gas compartment and terminating in said gas compartment above its highest liquid level.
7. In a gas-holder, comprising a gas compartment, a liquid compartment in the form of Mariotte's bottle, a communication pipe branching off from said liquid compartment and extending into said gas compartment and terminating in the latter above the floor thereof, the provision of an overflow pipe in the form of a float arrangement within said gas compartment around said communication pipe and dipping into mercury on the floor of said gas compartment and terminating in said gas compartment above its highest liquid level. 80
5. Gas-holder with constant pressure comprising in combination a gas compartment, a liquid compartment in the form of Mariotte's bottle, a communication pipe branching off from said liquid compartment and extending into said gas compartment and terminating in the latter above the floor thereof, an overflow pipe arranged within said gas compartment and branching off from said communication pipe and terminating in said gas compartment above its highest liquid level, and a shut-off device arranged at the lowest place of said pipes. 15
6. In a gas-holder, comprising a gas compartment, a liquid compartment in the form of Mariotte's bottle, a communication pipe branching off from said liquid compartment and extending into said gas compartment and terminating in the latter above the floor thereof, the provision of an overflow pipe in the form of a float arrangement within said gas compartment around said communication pipe and dipping into mercury on the floor of said gas compartment and terminating in said gas compartment above its highest liquid level. 20
